Inventor
Gustav A. Baeder
By Fabel & Mueller Atty.

UNITED STATES PATENT OFFICE.

GUSTAV A. BAEDER, OF CHICAGO, ILLINOIS.

CONDIMENT HOLDER.

Application filed July 31, 1922. Serial No. 578,701.

To all whom it may concern:

Be it known that I, GUSTAV A. BAEDER, a citizen of the United States, residing at Chicago, in the county of Cook and State 5 of Illinois, have invented a certain new and useful Improvement in Condiment Holders, of which the following is a full, clear, concise, and exact description, reference being had to the accompanying drawings, forming 10 a part of this specification.

My invention relates to condiment holders, and more particularly to a combined salt and pepper shaker.

It is a purpose of the invention to provide 15 a new and improved device of the above mentioned character which is an improvement over the patent granted to myself and George Lude, 918,115, patented April 13, 1909, and which is preferably made of 20 fibrous material and in halves which are secured together by any suitable adhesive material.

Other objects and advantages of the invention will appear as the description of 25 the accompanying drawings proceeds. However, I desire to have it distinctly understood that I do not intend to limit myself to the exact details shown or described, but that I intend to include as part of my in- 30 vention all such obvious changes and modifications of parts as would occur to a person skilled in this art and as would fall within the scope of the claim.

In the drawings:

Fig. 1 is a side elevation of my improved 35 condiment holder;

Fig. 2 is an inside elevation of one of the sections thereof;

Fig. 3 is a transverse vertical sectional 40 view of the device showing the two halves thereof separated; and

Fig. 4 is a view similar to Fig. 1 of a device of the above mentioned character having a toothpick holding device provided 45 thereon.

Referring in detail to the drawings, my improved condiment holder comprises the sections 5 and 5', which are preferably molded out of fibrous plastic material into 50 the desired shape. Each of said members comprise a side wall portion 6 that is substantially flat and end wall portions 7 and 8 which are suitably curved, and which are

provided with neck portions 9 and 10 threaded as shown at 11 and 12 for securing the 55 caps 13 thereon, said caps being removed in Figs. 1 and 2 but shown in position in Fig. 4. Each of said members 5 and 5' is provided with a top wall portion 14 which is curved in any suitable manner so as to 60 give a pleasing appearance thereto, and each of the sections is also provided with a vertically extending rib portion 15 which forms a partition extending between the top 65 wall portion 14 and the bottom wall portion 16 so as to form two chambers 17 and 18 within said device, one of said chambers being preferably used for salt and the other for pepper. The outer face of the wall portion 6 of the member 5 is preferably provided with a pair of flat faces 19 and 20 upon which any suitable indicating means may be provided to indicate the nature of the contents of the compartments. Said face is also preferably provided with a flat- 70 tened portion 21 upon which any suitable advertising means or other identifying means may be provided.

In the form shown in Figs. 1 to 3 inclusive the device serves merely as a condiment holder, but in the form shown in Fig. 4 the top wall portion 14' is provided with an upward extension 22 which is tubular in form, and which is threaded at 23, the partition 15 extending from the partition 24 between 75 said tubular portion 22 and the inner hollow of the container, and the bottom 16. Screwthreadedly mounted on the threads 23 is a cap 25 which is adapted to clamp the member 26 of elastic material between the 80 same and the end of the tubular portion 22. Said member of elastic material is provided with an opening 27 therein into which the toothpicks designated by the numeral 28 may be inserted. The member 26 is made of 85 elastic material so that the same can accommodate a varying number of toothpicks.

It is, of course, to be understood that the caps 13 and 23 may be secured in position in any other manner than by the screw- 90 threaded connection shown.

Having thus described my invention, what I desire to claim and secure by U. S. Letters Patent is:

A device of the character described com- 105 prising a body portion having a pair of

separate chambers therein, threaded inclined nipples communicating therewith, perforated shaker caps threaded on said nipples, a threaded tubular member projecting upwardly from said body portion, a perforated article gripping member of elastic material mounted thereon, and a flanged ring secured to said tubular member for clamping said elastic member against the end of said tubular member. In witness whereof I hereunto subscribe my name this 15th day of July, A. D. 1922.

GUSTAV A. BAEDER.
